COMBINED FISHERMAN'S BAIT BUCKET AND TACKLE BOX

Albert H. Edmonds and Robert A. Snider, Lancaster, Ohio

Application April 29, 1955, Serial No. 35,758

Term of patent 14 years

(Cl. D58—12)

FIG. 1.

FIG. 2.

FIG. 3.

FIG. 4.

Fig. 1 is a perspective view of a combined fisherman's bait bucket and tackle box showing our new design;

Fig. 2 is a top plan view;

Fig. 3 is a vertical sectional view taken along the line 3—3 of Fig. 2; and

Fig. 4 is a transverse vertical sectional view taken along the line 4—4 of Fig. 2.

We claim:

The ornamental design for a combined fisherman's bait bucket and tackle box, substantially as shown.
